UNITED STATES PATENT OFFICE.

JOHN HUSAR, OF CHICAGO, ILLINOIS.

KEY RING.

Application filed August 11, 1921. Serial No. 491,398.

To all whom it may concern:

Be it known that I, JOHN HUSAR, a citizen of the United States, and a resident of Chicago, in the county of Cook and State of Illinois, have invented a new and useful Improvement in Key Rings, of which the following is a full, clear, and exact description.

My invention relates to key rings, and it consists in the combinations, constructions, and arrangements herein described and claimed.

An object of my invention is to provide a novel form of key ring in which means is provided for normally maintaining keys in place thereon, while permitting removal of the keys at will.

A further object of my invention is to provide a device of the character described that combines in one article means for performing operations ordinarily requiring the use of a plurality of separate articles.

A further object of my invention is to provide a device of the character described that is compact in form and adapted to be carried about in the pocket of a garment, or in like places.

A further object of my invention is to provide a device of the character described in which the button-hook is locked in closed position.

Another object of my invention is to provide a device of the character described that can be manufactured cheaply, and is thoroughly practical commercially.

Other objects and advantages will appear in the following specification, and the novel features of the invention will be particularly pointed out in the appended claim.

My invention is illustrated in the accompanying drawings, forming part of this application, in which—

Figure 1 is a plan view of the preferred form of the device, and

Fig. 2 is a similar view of a modified form.

In carrying out my invention, I provide a body portion 1 that is stamped or otherwise formed in a single piece of general triangular form. I prefer to form the body portion 1 of a light metal, although any other suitable material, such as wood, fiber, or the like, may be used. The body portion 1 has contacting end portions 2 and 3, the latter being relatively reduced and provided with a ball end 4. An arm 5 is attached to the end portion 2 at the extremity of the latter by means of a pivot pin 6 or the like, the con-

nection being such that the arm 5 frictionally engages the end portion 2 and in consequence will normally remain in adjusted position with respect to the latter. The arm 5 is reduced adjacent to its outer end and is formed to provide a hook 7. The latter is adapted for use in the same manner as an ordinary button-hook.

The body portion 1 is also provided with an integral hook-like extension or lug 8. An extension 9 that is also integral with the body portion has a sharp edge 10 and cooperates with the body portion 1 and with a guide 11 projected transversely through the body portion adjacent to the extension 9 to adapt the device for use in performing the functions ordinarily requiring the use of a can-opener. A corkscrew 12 is pivotally attached to the body portion 1, as at 13.

From the foregoing description of the various parts of the device, the operation thereof may be readily understood. A key 14 may be slipped over the end of the arm 5 when the latter is in the position indicated by the dotted lines in Fig. 1. The key is then moved downwardly along the end portion 2 and is forced between the ball member 4 and the end portion 2, whereby the key will normally hang in the position illustrated. The end portion 3 may be moved under pressure away from the end portion 2 to permit the positioning of the key 14 in the manner described, and will then spring back into place. The arm 5 is then moved from the position indicated by the dotted lines in Fig. 1 into the position indicated by the full lines in the same figure. It will be observed that the hook 7 of the arm 5 has to first be flexed laterally so as to be received within the socket 15 in the body portion 1. The arm 5 now serves as a guard or keeper to protect the end portion 3 from shocks and jars and to also prevent the accidental displacement of the key 14 from the body portion 1.

The arm 5 now serves as a guard or keeper to protect the end portion 3 from shocks and jars and to also prevent the accidental displacement of the key 14 from the body portion 1. It is obvious that the arm 5 cannot accidentally swing open, since it first has to move laterally before the hook can be released from the recess 15. The hook 7 serves a double function, i. e., as a locking means for the arm 5, and as an ordinary button-hook.

The form of the device illustrated in Fig. 2 is substantially identical in essential respects with the form of the device illustrated in Fig. 1. Consequently, it is believed that a detailed description of the modified

form for carrying out the same invention will not be required herein. The same reference numerals have therefore been used to designate like parts throughout, and I shall 5 confine my description of the modified form to the parts thereof that differ from the corresponding parts of the preferred form of the device.

In the form of the device illustrated in 10 Fig. 2, the body portion 1 has an integral loop or ring extension 20 which replaces the lug 8 of the preferred form of the device and cooperates with the body portion 1 in adapting the device for use in removing 15 caps from bottles or like vessels.

It will thus be manifest that I provide a

simple, inexpensive article that can be carried about in a pocket and has a general utility that renders it particularly suitable for use in the household and while traveling. 20

I claim:

A device of the type described comprising a body portion having a substantially triangular-shaped key ring, the ring having a hook-shaped recess in the outer surface 25 thereof, and an arm pivotally carried by one end of said ring, said arm having a hook-shaped end adapted to be received in said recess, said hook and arm being fashioned so as to function as an ordinary button-hook 30 when in opened position.

JOHN HUSAR.
